CLAIM

The ornamental design for multiple station surge protector, as shown and described.

DESCRIPTION

FIG. 1 is a top perspective view of a multiple station surge protector showing my new design;

FIG. 2 is a top plan view thereof;

FIG. 3 is a left side elevational view thereof;

FIG. 4 is a right side elevational view thereof;

FIG. 5 is a bottom plan view thereof;

FIG. 6 is a front elevational view thereof;

FIG. 7 is a rear elevational view thereof;

The broken line showing is intended to illustrate environmental elements only and forms no part of the claimed design.

FIG. 1

FIG. 2

FIG. 3

FIG. 4

FIG. 5

FIG. 6

FIG. 7
